CONVERSION OF HYDROCARBON OILS

Kenneth Swartwood, Chicago, Ill., assignor to
Universal Oil Products Company, Chicago, Ill.,
a corporation of Delaware

Application June 27, 1934, Serial No. 732,606

3 Claims. (Cl. 196—48)

This invention particularly refers to an improved process and apparatus for the selective conversion of relatively low-boiling and high-boiling oils. It is particularly directed to the treatment of hydrocarbon oil charging stocks of relatively wide boiling range, providing for fractional distillation of the charging stock accompanied by relatively mild conversion of its high-boiling fractions (ordinarily termed viscosity breaking) accomplished without passing the same through a heating coil and provides for further conversion of the lower boiling fractions of the charging stock and the vaporous products resulting from relatively mild conversion of the high-boiling fractions of the intermediate conversion products of the process together with vaporous products resulting from more severe conversion of the low-boiling fractions of the intermediate conversion products.

One specific embodiment of the present invention may comprise subjecting a relatively low-boiling hydrocarbon oil, recovered from within the system, to relatively high conversion temperature at substantial superatmospheric pressure in a heating coil, introducing the highly heated products into a high-pressure reaction chamber wherein continued conversion, particularly of their vaporous components, is accomplished, withdrawing both vaporous and liquid conversion products from the reaction chamber and introducing the same into a reduced pressure vaporizing chamber, withdrawing residual liquid from the vaporizing chamber, subjecting vaporous products from the vaporizing chamber to fractionation whereby their insufficiently converted components are condensed as reflux condensate and separated into selected relatively low-boiling and high-boiling fractions, subjecting fractionated vapors of the desired end-boiling point to condensation and recovering the resulting distillate, returning the relatively low-boiling fractions of the reflux condensate, which comprise said relatively low-boiling oils recovered from within the system, to the heating coil for further conversion, subjecting the relatively high-boiling fractions of the reflux condensate to milder conversion temperature at substantial superatmospheric pressure in a separate heating coil, introducing the heated products into a separate reaction chamber also operated at substantial superatmospheric pressure, wherein vaporous and residual liquid conversion products are separated, simultaneously introducing charging stock for the process, comprising a hydrocarbon oil of relatively wide boiling range, into the last

mentioned reaction chamber whereby its relatively low-boiling and high-boiling fractions are separated and the latter are subjected to a relatively mild conversion or viscosity breaking operation, withdrawing non-vaporous residual liquid from the last mentioned reaction chamber and, when desired, introducing all or a regulated portion thereof into the reduced pressure vaporizing chamber, withdrawing vaporous products from the last mentioned reaction chamber, including said relatively low-boiling fractions of the charging stock and the vaporous products resulting from the relatively mild conversion of said high-boiling fractions of the reflux condensate, and introducing the same into the first mentioned reaction chamber whereby they are commingled and subjected to further conversion with the vaporous products from the first mentioned heating coil.

The accompanying diagrammatic drawing illustrates one specific form of apparatus embodying the features of the present invention. Referring to the drawing, heating coil 1 is located within a furnace 2 of any suitable form and relatively low-boiling oil, supplied to this zone from within the system, as will be later more fully described, is subjected thereto to a relatively high conversion temperature, preferably at substantial superatmospheric pressure, by means of heat derived from the furnace. The stream of highly heated products is discharged from the heating coil through line 3 and valve 4 and is introduced into reaction chamber 5 wherein its vaporous components commingle with other vaporous materials from within the system, supplied to this zone, as will be later more fully described, and wherein the commingled vapors are subjected to continued conversion.

Chamber 5 is also preferably operated at a substantially superatmospheric pressure and, although not illustrated in the drawing, it is preferably insulated to prevent the excessive loss of heat by radiation so that continued conversion of the heated materials supplied to this zone, and particularly their vaporous components, is accomplished therein. Both vaporous and liquid conversion products are, in the particular case here illustrated, withdrawn in commingled state from the lower portion of chamber 5 through line 6 and valve 7 and are introduced into vaporizing chamber 8.

Chamber 8 is preferably operated at a substantially reduced pressure relative to that employed in chamber 5 by means of which further vaporization of the liquid conversion products

supplied to this zone is accomplished. Vaporous and liquid conversion products are separated in chamber 8 and the residual liquid may be withdrawn therefrom through line 9 and valve 10 to 5 cooling and storage or to any desired further treatment while the vaporous products pass from the upper portion of chamber 8 through line 11 and valve 12 to fractionation in fractionator 13.

The components of the vaporous products supplied to fractionator 13 boiling above the range of the desired final light distillate product of the process are condensed in this zone as reflux condensate and the reflux condensate is separated by fractional distillation in this zone into 10 selected relatively low-boiling and high-boiling fractions. Fractionated vapors of the desired end-boiling point, comprising materials within the boiling range of the desired final light distillate product of the process and uncondensable 15 gas produced by the operation, are withdrawn from the upper portion of fractionator 13 through line 14 and valve 15 to condenser 16 wherein they are subjected to condensation and cooling. The resulting distillate and uncondensable gas passes 20 from condenser 16 through line 17 and valve 18 to collection and separation in receiver 19. Uncondensable gas may be released from the receiver through line 19 and valve 20. The distillate collected in receiver 18 may be withdrawn 25 from condenser 16 through line 17 and valve 18 to collection and separation in receiver 19. Uncondensable gas may be released from the receiver through line 19 and valve 20. The distillate collected in receiver 18 may be withdrawn 30 therefrom through line 21 and valve 22 to cooling and storage or to any desired further treatment. When desired, a regulated portion of the distillate collected in receiver 18 may be recirculated by well known means, not illustrated, to 35 the upper portion of fractionator 13 to serve as a cooling and refluxing medium in this zone whereby to assist fractionation of the vapors and maintain the desired vapor outlet temperature from the fractionator.

40 The selected relatively low-boiling fractions of the reflux condensate formed in fractionator 13 may be withdrawn from one or a plurality of suitable intermediate points in the fractionating column, passing, for example, through line 23 and valve 24 to pump 25 by means of which this relatively low-boiling oil is supplied through line 26 and valve 27 to heating coil 1, for further conversion as already described.

45 The relatively high-boiling fractions of the reflux condensate formed in fractionator 13 may be withdrawn from the lower portion of this zone through line 28 and valve 29 to pump 30 by means of which this material is supplied through line 31 and valve 32 to further conversion 50 in heating coil 33.

55 A furnace 34 of any suitable form supplies the required heat to the oil passing through heating coil 33 to bring it to the desired conversion temperature, preferably at a substantial superatmospheric pressure. Preferably, the conversion temperature to which the relatively high-boiling oil is subjected in heating coil 33 is milder than the temperature employed in heating coil 1 for treatment of the relatively low-boiling oil. The 60 heated products are discharged from heating coil 33 through line 35 and valve 36 and are introduced into reaction and separating chamber 37 which is also preferably operated at a substantial superatmospheric pressure and wherein vaporous 65 conversion products are separated from the residual liquid conversion products.

70 Simultaneous with the operation above described, charging stock for the process, preferably comprising an oil of relatively wide boiling range, such as crude petroleum, topped crude

or the like, is supplied through line 38 and valve 39 to pump 40 by means of which it is fed through line 41 and may be directed, all or in part, either through valve 42 in this line into line 35, to commingle therein with the stream of heated products 5 passing from heating coil 33 into chamber 37, or it may be directed, all or in part, from line 41 through line 43 into reaction chamber 37, entering this zone at any desired point or plurality of points either above or below the point of 10 introduction of the heated products from heating coil 33, as indicated in the drawing, by means of lines 44 and valves 45.

The charging stock supplied to chamber 37, either directly or by way of line 35, serves to partially cool and retard further conversion and vaporization of the heated products from heating coil 33 and the charging stock is thereby subjected to heating and to substantial vaporization in chamber 37. The charging stock may, of 15 course, be preheated in any well known manner, not illustrated in the drawing, prior to its introduction into line 35 and/or chamber 37. However, the quantity and temperature of the charging stock supplied to chamber 37 will ordinarily 20 be such that conversion in this zone is substantially limited to the relatively high-boiling fractions of the charging stock and of the conversion products from heating coil 33.

25 The residual liquid remaining unvaporized in 30 chamber 37, including relatively high-boiling fractions of the charging stock or the residual liquid resulting from its relatively mild conversion in chamber 37 and the residual liquid resulting from conversion of the relatively high-boil- 35 ing fractions of the reflux condensate, is withdrawn from the lower portion of chamber 37 through line 46 and may pass, all or in part, through valve 47 to cooling and storage or elsewhere, as desired, or may be directed, all or in 40 part, from line 46 through line 48 and valve 49 into vaporizing chamber 8, wherein it is subjected to further vaporization for the recovery of any desirable relatively low-boiling components suitable as cracking stock for treatment within 45 the system, which latter pass together with other vaporous products from chamber 8 to fractionation in fractionator 13, as already described.

50 Vaporous materials evolved from the charging stock in chamber 37, as well as the vaporous conversion products from heating coil 33 remaining uncondensed in chamber 37 are withdrawn from the upper portion of this zone through line 50 and valve 51 and are introduced into reaction chamber 5 wherein they commingle with the more 55 highly heated vaporous products from heating coil 1, serving to partially cool the same and prevent their excessive further conversion, and are subjected to continued conversion therewith in the reaction chamber and to the subsequent 60 treatment already described.

65 The preferred range of operating conditions which may be employed in accordance with the provisions of the present invention, in an apparatus such as illustrated and above described, 65 may be approximately as follows: The heating coil to which the relatively low-boiling fractions of the reflux condensate are supplied may utilize a conversion temperature measured at the outlet therefrom ranging, for example, from 900 to 70 1000° F., preferably with a superatmospheric pressure at this point in the system of from 200 to 500 pounds, or more, per square inch. The succeeding reaction chamber may be operated at substantially the same pressure as that employed 75

at the outlet from the high-temperature heating coil or may employ a somewhat reduced superatmospheric pressure. The heating coil to which the relatively high-boiling fractions of the reflux condensate are supplied preferably employs an outlet conversion temperature of from 850° to 950° F., with a superatmospheric pressure, measured at this point in the system, of from 100 to 500 pounds, or thereabouts, per square inch. Any desired pressure within substantially the same range may be employed in the succeeding reaction and separating chamber which pressure, however, is preferably not less than that employed in the reaction chamber to which the 15 vaporous products from this zone are supplied. The vaporizing chamber is preferably operated at a substantially reduced pressure relative to that employed in the reaction chambers which may range, for example, from 100 pounds, or 20 thereabouts, per square inch, down to substantially atmospheric pressure. The fractionating, condensing and collecting portions of the system may employ substantially the same or somewhat reduced pressures relative to that employed 25 in the vaporizing chamber.

As a specific example of the operation of the process of the present invention, as it may be accomplished in an apparatus such as illustrated and above described, utilizing as charging stock 30 a California crude of about 16° A. P. I. gravity, the light reflux heating coil employs an outlet conversion temperature of about 970° F. and a superatmospheric pressure of approximately 400 pounds per square inch which is reduced to approximately 250 pounds per square inch in the succeeding reaction chamber. A conversion temperature of approximately 920° F. is employed at the outlet from the heavy reflux heating coil with a superatmospheric pressure slightly in excess of 40 250 pounds per square inch at the outlet from this heating coil and in the succeeding reaction and separating chamber. The charging stock is commingled with the stream of heated products passing from the heavy reflux heating coil into 45 the reaction and separating chamber. The vapors from the last mentioned reaction chamber are supplied to the first mentioned reaction chamber wherein they are subjected to continued conversion and from which the vaporous and liquid products pass to a vaporizing chamber operated at a superatmospheric pressure of about 50 pounds per square inch. Residual liquid from the last mentioned reaction chamber is also supplied to the vaporizing chamber. The pressure 50 employed in the vaporizing chamber is substantially equalized in the succeeding fractionating, condensing and collecting portions of the system. This operation may produce, per barrel of charging stock, about 50 percent of 385° F. end-point motor fuel having an octane number of approximately 72 and about 40 percent of good quality residual liquid suitable as fuel, the remaining 10 percent, or thereabouts, being chargeable, principally to uncondensable gas and loss.

65 I claim as my invention:

1. In a process for the conversion of hydrocarbon oils wherein a relatively low-boiling oil recovered from within the system is subjected to conversion conditions of elevated temperature and superatmospheric pressure in a heating coil and communicating reaction chamber, the resulting vaporous and liquid conversion products separated in a reduced pressure vaporizing chamber, the vaporous conversion products subjected to fractionation, whereby their insufficiently con-

verted components are condensed as reflux condensate and separated into selected relatively low-boiling and high-boiling fractions, fractionated vapors of the desired end-boiling point subjected to condensation, the resulting distillate recovered, said low-boiling fractions of the reflux condensate returned to the heating coil for further conversion and said high-boiling fractions of the reflux condensate subjected to less severe conversion conditions of elevated temperature 10 and superatmospheric pressure in a separate heating coil, the improvement which comprises introducing heated products from the last mentioned heating coil into a separate reaction chamber, also operated at superatmospheric pressure, 15 and commingling therewith charging stock for the process, comprising an oil of relatively wide boiling range, vaporizing a substantial portion of the charging stock in said separate chamber, introducing vaporous products from said separate 20 reaction chamber, comprising vapors of the charging stock and vaporous products resulting from said conversion of the high-boiling fractions of the reflux condensate, into the first mentioned reaction chamber whereby they are commingled 25 and subjected to further conversion with the vaporous products from the first mentioned heating coil, and supplying residual liquid, comprising unvaporized portions of the charging stock and residual products resulting from said con- 30 version of the high-boiling fractions of the reflux condensate, to the vaporizing chamber in regulated quantities for further vaporization.

2. A conversion process which comprises fractionating hydrocarbon vapors to form a relatively heavy reflux condensate and a lighter reflux condensate, heating the latter to cracking temperature under pressure in a heating coil and then introducing the same to a reaction zone, simultaneously heating the heavy reflux condensate 35 under pressure to lower cracking temperature in a second heating coil and discharging the same into a separating zone maintained under pressure, introducing charging oil for the process to said separating zone and therein vaporizing a 40 substantial portion thereof, separating volatilized portions of the charging oil and of the heavy reflux condensate from unvaporized oil in the separating zone, introducing such volatilized portions to said reaction zone for conversion therein 45 in admixture with the heated lighter reflux condensate from the first-named coil, removing the conversion products from the reaction zone and introducing the same to a vaporizing zone maintained under lower pressure than the reaction 50 zone and said separating zone, discharging unvaporized oil from said separating zone into the vaporizing zone and separating vapors from residue in this zone, supplying the former to the fractionating step as said hydrocarbon vapors, and 55 finally condensing the fractionated vapors.

3. A conversion process which comprises fractionating hydrocarbon vapors to form a relatively heavy reflux condensate and a lighter reflux condensate, heating the latter to cracking temperature under pressure in a heating coil and then introducing the same to a reaction zone, simultaneously heating the heavy reflux condensate under pressure to lower cracking temperature in a second heating coil and discharging the 70 same into a separating zone maintained under pressure, introducing charging oil for the process to said separating zone and therein vaporizing a substantial portion thereof, separating the resultant vapors of the charging oil and of the 75

heavy reflux condensate from unvaporized oil in the separating zone, introducing the last-named vapors to said reaction zone for conversion therein in admixture with the heated lighter reflux condensate from the first-named coil, removing the conversion products from the reaction zone and introducing the same to a vaporizing zone maintained under lower pressure than

the reaction zone and said separating zone, discharging unvaporized oil from said separating zone into the vaporizing zone and separating vapors from residue in this zone, supplying the former to the fractionating step as said hydrocarbon vapors, and finally condensing the fractionated vapors. 5

KENNETH SWARTWOOD.
